UNITED STATES PATENT OFFICE.

WILLIAM KIRCHMAN, OF VAN BUREN, ARKANSAS, ASSIGNOR TO THE ENGINEERING WORKS, OF VAN BUREN, ARKANSAS, A CORPORATION OF ARKANSAS.

MINING CAR.

1,417,834.

Specification of Letters Patent. Patented May 30, 1922.

Application filed April 19, 1921, Serial No. 462,632. Renewed April 18, 1922. Serial No. 555,234.

To all whom it may concern:

Be it known that I, WILLIAM KIRCHMAN, a citizen of the United States, and a resident of Van Buren, in the county of Crawford 5 and State of Arkansas, have invented certain new and useful Improvements in Mining Cars, of which the following is a specification.

This invention relates to a mining car, 10 and particularly to the structure thereof.

The object of the invention is to provide a car of the above character which is made up of standard units and sections, said units and sections being adapted for casting or 15 otherwise forming previous to their assembly for forming the car.

It is also an object of the invention that the sections forming the body of the car be adapted for varying the width thereof.

20 Other object and objects relating to details of construction, combination and arrangement of parts will hereinafter appear in the detailed description to follow.

The invention is illustrated by way of example in the accompanying drawings, in which—

Figure 1 is a bottom plan view of an assembled car embodying my invention,

Figure 2 is a side elevation of the same,

30 Figure 3 is an end elevation,

Figure 4 is a side elevation of an axle casting showing the stub shafts for journaling the car wheels, as attached,

Figure 5 is a top plan view of an axle 35 casting, the stub shafts for journaling the wheels being removed,

Figure 6 is an end elevation of the axle casting as shown in Figure 4, and the stub shaft connected therewith being shown in

40 cross section,

Figure 7 is a detail perspective view of a bumper.

Referring to the drawings more particularly A indicates a pair of end sections and 45 B a pair of central sections. Each of the end sections comprise a bottom panel 10 and a pair of side panels 11, said panels being secured together as shown. Also the end sections A are each provided with a pair of

50 end panels 13 and 14 cut away as shown, to accommodate the car wheels. Upon each adjacent edge of the panels 13 and 14 there is bolted a strap 15, and between the straps 15 there is secured a filler plate 16, said filler

55 plate being adapted to permit the width of

the car body to be increased when so desired. The middle sections B and end sections A are secured to each other by the means of the straps 17, said straps being similar to the straps 15 and each being formed with a central rib 18 for strengthening the same. Also the straps 15 are each formed with a rib 18 for a like purpose. The rear pair of end panels 13 and 14 of the corresponding end section A are free from said section and 60 secured to a pair of arms 19 by the means of the straps indicated at 20, said arms being pivoted at their forward ends to the pins 21 which project from the side panels 12. As is obvious from this construction, the 70 rear panels 13 and 14 are free for vertical swinging movement.

For the axles of the car I provide a casting as shown in detail in Figures 4 and 5, said casting consisting of two side portions 75 22 which are integrally connected by the bridge or bottom 23, said bridge or bottom being preferably of the shape shown in Figure 4. Each of the side portions 22 are formed with a series of lugs 24, and each of 80 said lugs formed with a central opening adapted to receive a bolt by which said axles may be bolted to the bottom of the car body. At each end of the axle casting there is formed integrally therewith a split sleeve 25, 85 said sleeve being adapted to receive the one end of a stub shaft 26. Each end of the sleeves 25 is formed with a pair of alined ears 27 through which holes are provided for receiving the bolts 28, said bolts being 90 adapted to bring the divided edges of the split sleeves together for binding the stub shaft within said sleeve against removal.

Also it is preferable that the stub shaft have recesses as indicated at 29 Figure 6, 95 which register with recesses 30 (Figure 5) formed in the split sleeves 25. The bolts 28 extend within the recesses 30 and also engage in the recesses 29 and in this manner further hold the stub shafts 26 against displacement or removal. Upon each of the stub shafts 26 there is formed a collar 31 which is adapted to limit the inward movement of the wheels 32 upon said stub shafts.

Upon each bottom panel 10 there is secured a bumper 33, said bumper consisting of the casting as shown in detail in Figure 7 and having a plurality of openings 34 through which the bolts may extend for securing the same to the bottom panels 10. 105 110

From the foregoing description it is thought that the advantages of the present invention can be clearly understood. It may be here pointed out that should any unit of 5 a car be broken, the same may be quickly replaced by substituting a unit of the same kind in stock. It may be also here mentioned that the different sections and panels are preferably secured together by means of 10 bolts which increase the flexibility of the car structure as a whole, thus enabling it to more easily retain its position upon the rails.

I claim:

1. An end section for a car body of the 15 class described, comprising a pair of side panels each carrying an end panel and the outer lower corner of each end panel being cut away to accommodate the car wheels, and connecting means between the end panels 20 adapted to permit the distance therebetween to be increased or decreased.

2. An end section for a car body of the

class described, comprising a pair of side panels each carrying an end panel and the outer lower corner of each end panel being 25 cut away to accommodate the car wheels, and a filler plate secured between the adjacent edges of the end panels whereby the distance between said end panels may be increased or decreased. 30

3. An end section for a car body of the class described, comprising a pair of side panels, each carrying an end panel and the outer lower corner of each end panel being cut away to accommodate the car wheels, a 35 filler plate between the adjacent edges of said end panels adapted to permit the distance therebetween to be increased or decreased, and strap means adapted for securing said filler plate to the end panels of said section and also adapted to reinforce said 40 filler plate.

WM. KIRCHMAN.
